UNITED STATES PATENT OFFICE.

EDWARD FEAGLER STANTON, OF LOS ANGELES, CALIFORNIA.

MARKING EXHIBITOR.

Application filed July 9, 1926. Serial No. 121,464.

This invention relates to improvements in marking exhibitors, having for an object to provide a novel and advantageous form of price card holder especially desirable for use 5 in designating prices of shelved commodities or other matter, the construction of the holder being such as to permit the removable arrangement of a price card therein together with its display in a most efficient manner, 10 whereby to positively indicate the prices of those commodities with which it is associated.

It is also an object of the invention to provide a holder of the character mentioned, 15 the shape of which is such as with introduction of a card thereinto, such card will be prevented from longitudinal displacement and also, that the holder will occupy but a minimum place, permitting the unimpeded 20 display and removal of the shelved articles with which it is associated, in addition to clearly displaying the price marking thereon.

Another and equally important object of 25 the invention may be stated to reside in the provision of a card holder having means thereon for permitting the quick introduction of a card thereinto and for engaging such card in a manner to retain the same 30 against lateral displacement, in that the corners of the card will be positively engaged in retaining means against outward movement whereas the intermediate portions of the card will be engaged and held against 35 inward displacing movement.

Other objects of the invention will be in part obvious and in part pointed out hereinafter.

In order that the invention and its mode 40 of operation may be readily understood by those skilled in the art, I have in the accompanying illustrative drawings and in the detailed following description based thereupon, set out one possible embodiment of the 45 invention.

In these drawings:

Figure 1 is a perspective view of the improved marking exhibit or card holder showing the arrangement of a card therein,

50 Figure 2 is a reverse perspective view of the holder,

Figure 3 is a front elevation of the same,

Figure 4 is an enlarged longitudinal section through the holder taken on the line 66 4-4 of Figure 1, looking in the direction in which the arrows point, and

Figure 5 is a transverse section taken on the line 5-5 of the Figure 2 looking in the direction in which the arrows point.

Having more particular reference to the drawings, in connection with which like characters of reference will designate corresponding parts throughout, the improved card holder may be stated to comprise a multi-sided frame of suitable metal or other material generally indicated at this time by the numeral 1, said frame being preferably triangular in shape or configuration and having inturned or inwardly disposed marginal flanges generally indicated by the numeral 2 formed upon the outer portions of the various sides of said triangular frame, while web portions 3 are formed integral with the sides of the frame 1 adjacent their points of jointure at the three corners of the same, as is clearly shown in the Figures 1, 2 and 3, it being noted in this connection, that the web portions 3 are flush with the outer sides or surfaces of the three sides of the triangular frame 1. Also, a finger is arranged 80 intermediately of and integral with the upper side of the frame 1, such finger being designated by the numeral 4 and having the free portion thereof rolled or flanged as at 5 whereby to pivotally receive the basal portion of a staple 6 or similar fastening device whereby the tag or card holder may be conveniently secured in a desired position adjacent shelving or other matter, as the case may be.

The web portions 3 spanning the various corners of the triangularly shaped frame 1, obviously, serve as means for preventing outward lateral displacement of a display card C engaged therein whereas the interned flanges 2 upon the various sides of such frame serve to prevent longitudinal displacement of the card with respect to the frame subsequently to its introduction thereinto. In order that such card C will be prevented 95 from having inward lateral displacing movement with respect to the triangularly shaped frame 1, elongated ears 7 are provided, these ears being formed integral or otherwise suitably attached to the inner marginal and intermediate portions of the opposite angular sides of the frame 1 in the manner clearly shown in the Figures 3 and 5. In this particular embodiment of the invention, it will be noted that the ears 7 are shown as being 105 formed integral with the angularly opposed sides of the frame 1, said ears being disposed

inwardly with respect to the outer surfaces or face of the frame 1 as is shown in the Figures 3 and 5 and likewise, laterally and inwardly offset from the web portions 3 spanning the various corners of the frame 1; those portions of the ears 7 adjacent or adjoining their respective frame sides being formed with right angularly shaped shoulders as indicated by the numeral 8, thus providing an effectual seat for the adjacent marginal portions of the card C with introduction of the same thereinto, as is shown in the Figure 5.

In usage of my improved price card holder, it will be understood that a price card of triangular formation is employed, the size of such card being such as to be snugly received within the inturned flanges 2, aforesaid. To engage the card C in the frame for displaying purposes, one extremity thereof is passed downwardly into and rearwardly of the lowermost web portion 3, in the fashion shown in dotted lines in the Figure 1, whereupon the opposite sides and intermediate portions of said card are arranged upon and forwardly of the ears 7; the opposite extremities of said card being arranged rearwardly of and adjacent the remaining web portions 3 spanning the other corner portions of the frame 1. With the price card C so engaged in the frame 1, it will be understood that the inturned flanges 2 will serve as effectual means for preventing longitudinal displacement of the card with respect to the frame, while the web portions 3 spanning the corners of said frame 1 will serve to prevent lateral and outward displacement of the card, whereas the ears 7 will afford effectual means for preventing inward lateral displacement of the card with respect to the frame, said card C will be effectually secured in a supported and displaying position within the frame 1. However, when desired, the card may be readily disengaged from the holder merely by flexing the upper and wider portion thereof outwardly beyond the adjacent portion of the inturned flange 2, following which the card may be then moved vertically so as to completely remove it from the remaining web portions 3 and the supporting ears 7.

From the foregoing it will be understood that I have provided a simple yet highly practicable and efficient form of marking exhibitor or price card holder, the construction of the holder being such as to permit of the convenient arrangement of a price marking card therein and at the same time, to allow of the quick and convenient removal of such card from the holder when it is desired. Also, because of the triangular formation of the holder together with the mode of supporting or suspending the same from shelving or other objects, it will

be understood that the holder will occupy but a minimum amount of space and by consequence, will not interfere with effectual display of the commodities or articles with which it is associated and similarly, because of its occupying but a minimum amount of space, will not impede the removal of the shelved goods when desired. Likewise, because of the fact that the securing device or staple 6 is pivotally connected to the finger 4, it will be understood that should the holder interfere with engagement or movement of shelved articles associated therewith, said holder may be swung upwardly and outwardly to an out of the way position. Following removal of the shelved articles or viewing of the same, the card may be then dropped to its original displaying position.

Manifestly the construction shown is capable of considerable modification, and such modification as is within the scope of my claims, I consider within the spirit of my invention.

I claim:

1. A device of the character described comprising a frame tapered towards one end thereof, webs integral with and spanning the corner portions of the frame, ears integral with the inner marginal portions of the frame sides and arranged laterally and inwardly of said webs adapted to have supporting engagement with adjacent sides of a card, a flange upon the normally upper and remaining side of the frame bent inwardly whereby to lock the card received between the webs and ears against longitudinal displacement from the frame, and attaching means connected to the normally upper side of the frame.

2. A device of the character described comprising a frame tapered towards one end thereof, the outer marginal portions of the various sides of said frame being formed with inwardly bent flanges, webs integral with and spanning the various corner portions of said frame, ears integral with the inner marginal portions of certain of the sides of said frame, said ears being arranged laterally and inwardly with respect to the webs and inwardly of the extremities of the flanges upon the sides of said frame adapted to have supporting engagement with the adjacent sides of a card, that flange formed upon the normally upper side of the frame overlying the adjacent marginal portion of the card whereby to lock the same against longitudinal displacement from the frame, and attaching means upon the normally upper side of said frame and intermediately thereof.

In witness whereof I have hereunto set my hand.

EDWARD FEAGLER STANTON.
